Primary Examiner — George D Kirschbaum*Assistant Examiner* — Natasha Vujcic(74) *Attorney, Agent, or Firm* — Downs Rachlin Martin PLLC(57) **CLAIM**

The ornamental design for a display panel frame, as shown and described.

DESCRIPTION

FIG. 1 is a perspective view of a display panel frame showing our new design;

FIG. 2 is a front view thereof;

FIG. 3 is a rear view thereof;

FIG. 4 is a side view thereof;

FIG. 5 is a second side view thereof;

FIG. 6 is a cross section taken along line 6-6 of FIG. 2;

FIG. 7 is a top view thereof; and,

FIG. 8 is a bottom view thereof.

The broken lines in the Figures are for the purpose of illustrating unclaimed portions of the display panel frame and form no part of the claimed design.

The shade lines in the Figures show contour and not surface ornamentation.

1 Claim, 5 Drawing Sheets(56)
